UNITED STATES PATENT OFFICE

GEORGE SHERMAN, OF NEWTON, MASSACHUSETTS, ASSIGNOR TO SHERMAN PAPER PRODUCTS CORPORATION, OF SOUTH BOSTON, MASSACHUSETTS, A CORPORATION OF MASSACHUSETTS

DESIGN FOR A PAPER CONTAINER

Application filed February 20, 1932. Serial No. 42,949. Term of patent 7 years.

To all whom it may concern:

Be it known that I, GEORGE SHERMAN, a citizen of the United States of America, residing at Newton, in the county of Middlesex and Commonwealth of Massachusetts, have invented a new, original, and ornamental Design for Paper Containers, of which the following is a specification, reference being had to the accompanying drawing, forming a part thereof.

In said drawing:

The figure is a perspective view of a container showing my new design.

I claim:

The ornamental design for a paper container as shown.

Signed by me at Boston, in the county of Suffolk, and Commonwealth of Massachusetts, this 15th day of February, 1932.

GEORGE SHERMAN.
